WEIGHT ACTUATED MECHANISM AND
MACHINE

Peter G. Crisafulli, Newark, N. J.

Application May 6, 1948, Serial No. 25,375

11 Claims. (Cl. 194—9)

1.

This invention deals with a weight-actuated mechanism and with machines incorporating such mechanism. More specifically, it relates to a weight-actuated lever arm pivoted near the center, the actuation being accomplished by gravity action of a weight dropped over the lower portion of the arm and to coin vending and dispensing units, and other machines of a similar character.

Conventional dispensing machines now require highly complicated electrical circuits, moving mechanisms and expensive switches in order to maintain a reasonably high efficiency. Yet, in spite of these features, the maintenance problem in conjunction therewith is a serious one, and expert technicians are required as trouble shooters and servicemen. In such units, considerable arcing, fusing, pitting and coating of contacts take place, since each contact generally closes an electrical circuit to prepare the machine for the next succeeding electrical or mechanical operation. In many instances a D. C. arc is too hot for switches in the machines, so that such machines can operate only on A. C. Most of the difficulty is due generally to the large number of parts, particularly moving parts, which incur the danger of jamming, high maintenance costs and the like.

Much of the serious trouble incurred with present day dispensing machines occurs in the coin registering mechanisms which are generally micro-switch and solenoid combinations. A considerable portion of the cost of such machines is also due to the expensive die-casting incurred.

There are many other disadvantages of conventional machines which will be mentioned in the discussion to follow.

One object of the present invention is to provide a simple cheap actuating unit and assembly, the parts of which may be all produced on a power press from sheet metal, thereby eliminating die casting and similar expensive forming operations. Another object is to incorporate only a small number of moving parts traveling for a short distance only, thereby reducing wear to a minimum and giving the apparatus a long life. A still further object is to provide a circuit wherein the contacts close in succession, operating in an open circuit up to the final actuating operation for the dispensing or other final operation of the machine, whereby arcing at the contacts is practically eliminated and no condensers are found necessary across practically all of the switch contact points, and fusing, pitting and other switching difficulties are reduced to a bare minimum.

A further purpose is to provide a machine which may be operated either by D. C. or A. C. without any inconvenience or difficulty and which will entail a low maintenance cost due to the unique design and simplicity of construction and require only inexperienced trouble shooters and maintenance men. Other purposes will be apparent from the description which is to follow.

The invention will be more readily understood by reference to the drawings in which Figure 1 is a front view of the lever arm actuating mechanism while Figure 2 is a side view thereof as indicated by line II—II of Figure 1. An isometric front view of the housing channel for the actuating assembly is shown in Figure 3. Figure 4 depicts an isometric front view of the coin gate which fits and slides within the channel shown in Figure 3. Figure 5 illustrates a front view of the channel or channel housing showing the stacked weight-actuated lever arms ready to be actuated by falling weights. A front view of a complete assembly of one embodiment of this invention is shown in Figure 6, as applied to a coin vending machine. Figures 7—10 are phantom side views in simplified form, showing the successive steps in the operation of an assembly such as that depicted in Figure 6, while Figure 11 illustrates a schematic electrical diagram illustrating the wiring employed for a vending machine employing the mechanism of the present invention as illustrated in Figure 6 and adapted to be activated after insertion of five coins. Similar numbers refer to similar parts in the various figures.

Referring again to the figures, and particularly to Figures 1 and 2, numeral 1 represents a lever arm having projecting side lugs 7 and 8 which project forwardly. The upper portion of lever arm 1 is preferably bifurcated with side prongs 2 and 3 straddling centrally disposed open space 6 (mainly for weight saving), prongs 2 and 3 being beveled at the upper back edges 14 to facilitate continuous riding over the front surface by coins or weights when the prongs are contacting the back wall of channel housing 19 (Fig. 2). The lower portion 4 of arm 1 is preferably narrowed to a centrally disposed strip, bent forwardly at point 5 at an angle of about 20°. Lower portion 4 is extended sufficiently so that it projects through the central opening of the back wall 39 of coin gate 33 (Fig. 4) when arm 1 is not actuated by coin 81, and said portion 4 is almost in juxtaposition with back wall sections 41, 43, etc. of coin gate 33 when arm 1 is actuated by a coin. Lugs 7 and 8 are provided with later-

ally disposed holes 86 in which is held wire 9, in loose pivoted relation, at a point somewhat below the center of gravity of lever arm 1. One end 10 of wire 9 projects from lug 8 to act as a support for lever arm 1 in channel housing 19. This wire 9, is bent and extended under lower portion 4 of arm 1 (somewhat above the middle section of said lower portion) and bent again in reverse direction and allowed to protrude outwardly through lug 7, the protrusion being bent into arm 12 and lever handle 13 which acts as the actuating means for completing a circuit or performing other electrical or mechanical operation upon actuation of lever arm 1 by a weight. Horizontal portion 87 of wire 9 extending from lug 7 (Fig. 1) serves as a pivot shaft for holding the other side of lever arm 1 in side 20 of channel housing 19.

As is shown in Figure 2, a coin falling from slot 17 and chute 68 falls along the forward side of bifurcated arms 2 and 3 and down over the front surface of lower projection 4, whereupon the weight of the coin causes the upper section of lever arm 1 to tilt forward on pivots 10 and 87, thereby pushing backward wire arm 11 which, in turn, causes protruding lever arm 13 to move forward thereby closing the switch or other mechanism to be actuated. As is apparent from Figure 2, when this occurs, the back surface of upper arms 2 and 3 become flush with the wall of chute 68, thereby allowing the succeeding coin to slide along the back surface of lever arm 1 onto the front surfaces of the bifurcated upper arms of the next lower lever arm 94' (Fig. 5) which is shaped and mounted similarly to lever arm 1 at a point immediately under lever arm 1. Succeeding coins thus actuate succeeding levers such as 13', which then actuate their adjacently disposed switches, until the lowermost lever arm 84, is made available for coin actuation. Up to this point, if lever arms 13 and 13' are employed for closing switches, such switches still may be in an open circuit, which circuit stays open even after actuation of lever arm 84 and switch actuating arm 85, which makes the unit ready for dispensing or other operation. The latter operation is effected by a switch such as 71 (Fig. 6), or a merchandise selector switch which then closes the entire circuit. Any succeeding coins inserted in slot 17 (Fig. 5) after the lowermost lever arm 84 has been actuated by means of a coin (before the circuit is closed by switch 71), will be uninterrupted in travel and will continue through chute 68 and emerge into coin return hopper 69 (Fig. 6).

It is desirable that all sharp edges and protrusions in the line of coin travel be beveled off so that the coin is not hindered in its travel. For this reason it is desirable to bevel off edge 99 on both sides of arm 1. Lever 13 is insulated by sleeve 98 having collar 97 fitting over contact 62 so that sleeve 98 cannot slip off.

It will be apparent that when the last coin is inserted into the lowermost arm, the circuit is complete and is ready to be closed for dispensing of the article purchased, by throwing a merchandise dispensing switch such as switch 71 (Fig. 6). When a single product is to be dispensed, the switch is preferably a 2-way switch as shown by 71. When thrown one way to return the coins in the machine, it may actuate solenoid 72 (Fig. 6), which pulls down arm 74 pivoted at 75 to a fixed pivot on mounting or base 79. It will be observed that arm 74 is pivotally attached to arm 71 of solenoid 72. The left end 78 of arm 75 chute 67 (Fig. 6) which deflects the coins into

14 is in pivoted relation to pivot post 59 projecting forwardly from the upper portion of back wall 39 of coin gate 33. As lever arm 74 is pulled down, coin gate 33 is also pulled down since it is attached to post 59.

Coin gate 33 (Fig. 4) is mounted inside channel housing 19 (Fig. 3) in vertical sliding relation thereto. This coin gate has narrow side walls 34 which are provided with inwardly directed front lips 36 and 37 for retaining the coins traveling within the gate, the gate being wide enough for the coins to travel easily edgewise therein. The upper and lower front faces of lips 36 and 37 have attached thereon plates 50, 53, etc. which protrude as bearing surfaces 48, 51, etc. from sides 34 and 35 of gate 33. Curved bottom portions 49, 52, etc. on these protrusions are provided to facilitate easy movement of the bearing surfaces 48, 51, etc. which ride over the cut-out side edges 22 and 29 of channel 19. The lower edges 23, 30, etc. of cut-out portions 22, 29, etc. are beveled (at 23 and 30) to allow travel thereon of bearing surfaces 48, 51, etc., this inclined-plane movement causing a forward movement of gate 33 with respect to channel 19, separating the gate from the channel. Gate 33 is flexibly mounted in channel 19 and is retained therein by springs 25 anchored at points 24 and looped around pins 26 to provide springiness, and extending over the outer side edges of channel 19. Springs 25 are also bent inwardly through slots 27 and 28 and project therethrough so that bent ends 16 (bent at 15) of springs 25 press against the faces of lips 36 and 37 of gate 33.

As stated previously, coin gate 33 has a cut-out open space (at 38, 46, etc.) in its back wall 39, the remaining portion of the back being present as retaining ends 41, 43, etc. serving to retain the coins 81, 82, etc. (Fig. 6) falling on lower portions 4, etc. of lever arms 1, etc. Slots 40, 42, 45, etc. are provided in these remaining back strips, the upper edges of the slots being almost in juxtaposition with the lower edges of the arm portions 4 of lever arms 1.

The action of solenoid 72 causes gate 33 to be pulled downwardly and outwardly with respect to channel 19 and the arms 1 holding coins 81, thereby allowing the coins to drop through the open space 91 (Fig. 10) and into chute portion 50 46 having lower deflecting arm 55, thereby causing the coins to travel through chute 68 into coin return hopper 69 (Fig. 6).

In the event the material purchased is to be dispensed, switch 71 is thrown in the opposite direction than heretofore described for coin return, thus simultaneously with the dispensing operation, causing actuation of solenoid 73, pulling solenoid arm 76 pivoted to end 88 of the lever arm pivoted to base 79 at 75, which causes the other end 78 of arm 74 to be raised, which in turn causes raising of coin gate 33, the bearing surfaces 48, 51, etc. of which slide upwardly on cut-out edges 22, 29, etc. Bearing surfaces 48, 51, etc. are attached to lips 36 and 37 by means of soldered plates 50, 53. During this movement, there is no forward motion of gate 33 separating it from channel 19. This upward motion allows slots 40, 42, 45, etc. in back wall 39 of gate 33 to come into juxtaposition with the lower edges of coins 81, 82, etc., thus causing the coins to slip through these slots (40, 42, etc.) and ride downwardly inside space 90 of gate 33 (Fig. 9), lips 36 and 37 preventing the coins from falling out of the gate. These coins continue downwardly and spill into 70 78 chute 67 (Fig. 6) which deflects the coins into

coin box 70 as payment for the material dispensed.

Inclined planes 47 attached to strips 57 on front lips 36 and 37 of gate 33 are disposed to slip under bent ends 16 of springs 25 in order to facilitate more rapid return of the gate after shutting off of power from the solenoid 73.

Switches 60, 63, 64, etc. are attached to one side 20 of channel 19 and are provided with contact points 62, etc. which are closed by levers 13, 13', etc. attached to lever arms 1, etc. Wire 61 is a lead to the first switch while wire 66 is a lead from the final switch completing the coin actuating circuit.

The operation of the machine illustrated in Figure 6 is depicted schematically in Figures 7-10. Figure 7 showing the lever arms in inactive position. Figure 8 shows four of the lever arms raised by coins resting against back walls 41, etc. of coin gate 33. When coin 89 is dropped into the last lever arm (84), the operating circuit is closed up to the open dispensing switch 71 (Fig. 6), and when this switch is tripped for dispensing the product purchased, coin gate 33 is raised as in Figure 9 until slots 40, 42, etc. are in juxtaposition with the bottoms of the coins 81, etc., thereby allowing the coins to fall therethrough edge wise into coin gate space 91 and finally into the cash box 70. If switch 71 is tripped for the purpose of returning the coins to the prospective purchaser, coin gate 33 is moved downwardly and outwardly, and the coins fall through space 91 (Fig. 10) between the bottom edges of the lever arms 1 and the back wall strips 41 of the coin gate, over deflector 55, and thence into coin return hopper 69. It will be observed that in the present system the coins stack from the top down whereas, in conventional systems now in use, the coins stack in the reverse direction, i. e., from bottom up.

It is apparent from this description that practically all of the parts may be produced from pressed sheet metal and there is no necessity for employing die-cast parts. Furthermore, the moving parts travel over only a short distance and the unit possesses a long life. Another inherent advantage is the fact that only a small number of parts are required, these parts being simple in construction, thereby eliminating the need for highly trained technical personnel for trouble shooting and maintenance.

The coin gate hold down springs 25 act as neutral positioners for coin gate 33 mounted in channel 19, since they act to pull gate 33 down from the inclined planes or ramps 47 to the neutral position, where the gate is ready again to receive coins from slot 17. Unnecessary duplication is eliminated by using the same springs 25 to return gate 33 after actuation or moving of the gate for discharging coins into either chute.

The bent wire levers 13, etc. attached to coin holder lever arm 1, etc. serve a dual purpose to support the coin holder lever arms (upon actuation) and also to operate the electrical contacts, thereby eliminating the need for rivets for holding arms, etc.

Flat bearing lugs 48, 51, etc., not only act as bearing surfaces for the coin gate but also act to maintain proper clearance between the gate and coin holder lever arms 1. Actuation of the coin gate can be accomplished by direct linkage to an outside lever which can be linked for either coin discharge or dispensing operations by means of a single lever arm, although the use of solenoids makes the unit more fool-proof and places under 75

control the force imposed on the machine. The present unit may be modified to allow dropping coins into a partitioned chute leading to a partitioned coin box which would segregate nickels, dimes, quarters, etc. for easier counting.

Figure 11 represents the electrical circuit employed for the operation of the unit illustrated in Figure 6. Voltage is applied at terminals 135 and 136, and a branch line 137 from line 136 leads to coin return solenoid 72, the other terminal of which is attached to contact 141 of switch 71. Common terminal 138 of switch 71 is led to outlet 135.

From the juncture with line 137, line 136 connects with line 139 to which are connected, in series, switches 60, 65, etc. which are actuated by lever arms 1, 84, etc. when they, in turn, are actuated by coins 81, 89, etc. The terminal of last switch 65 is connected with line 145 leading to terminal 143 which connects with the dispensing motor or merchandise selector switch. The other terminal 142 of this connection is connected to line 140 leading to coin collecting solenoid 73, the other terminal of which is connected with contact 144 of switch 71.

It will be observed that any coins present in lever arms which actuate switches 60, 65, etc. may be returned to the customer by actuating solenoid 72 with switch 71. However, actuation of solenoid 73 cannot be accomplished unless all of the five coins are present and are actuating the lever arms which actuate switches 60, 65, etc. When all of the coins are present, actuation of solenoid 73 by switch 71 will close the circuit up to connection 142-143 for the dispensing operation. Channels, lever arms and gates are provided for each type of coin. In this case there would be three channel-gate assemblies, but they all may be connected to common coin hoppers.

Although most of the discussion herein has been directed mainly to the application of the present device to coin dispensing machines, the weight-actuated device is applicable to any actuating mechanism to be actuated (in each gate) by means of substantially regular shaped weights of substantially equal weight. In other words, different weights may be used in different coin gates, all of which may be connected electrically and/or mechanically to the proper circuits and coin discharge hoppers.

Various modifications of the present device are possible. For example, it is possible to control carefully the width of space 91 in Fig. 8 so that thinner coins such as dimes may fall through upper arms and be caught by proper spacing in lower arms, while the upper arms may catch and hold thicker coins, such as nickels, for example.

As in other machines, slugs may be rejected in the present machine by inserting a slug detector unit in the coin chute above the coin actuated lever arms, there being a separate chute provided to discharge the rejected slugs into the coin return hopper.

Instead of the wire 9 for actuating the extraneous device (e. g. switch 13), the lever 13 may be directly attached to lever arm 1 by welding, soldering, etc. so that it moves with arm 1. Other actuating means may be provided, instead of lever 13, for actuating an external device, such as a switch or electrical contact under each lower portion 4 of arm 1, for example, in which case proper insulating precautions would necessarily have to be taken.

The raising of the gate can be called the coin

collecting position of the gate, while the lowering and separating operation of the gate may be termed as the coin return operation. However, such operations need not be limited to such uses and it is apparent that, with proper changes obvious to those skilled in the art, the uses for these operations may be reversed. Also, the hoppers for holding the dropped coins may be employed either for returning or collecting the coins.

As stated previously, although the use of this mechanism has been applied particularly to coin dispensing machines, it may be used in other mechanical or electrical operations, as for example, in cases where a weight is dropped on the lever arm 1 for a certain period for actuating an external device, and then lifted again.

I claim:

1. In a weight actuated unit for actuating an extraneous device, wherein the weight is fed edge-wise through a chute into the unit down a substantially vertical channel having side walls and a back, into the upper portion of which the chute feeds, and having at least one uprightly disposed lever arm having an upwardly projecting portion and a downwardly and forwardly projecting portion, said lever arm being pivotally mounted near its center and at its sides to the sides of said channel far enough away from the back wall of the channel to allow sufficient room behind the pivoted portion of said lever arm to allow another weight to pass therethrough when said lever arm is actuated by a weight, said actuating weight resting on the lower portion of the lever arm below the pivot when it actuates the lever arm by moving forward the upper projecting portion of said arm, the improvement comprising movable retaining means in front of the lower portion of the lever arm for holding said weight and preventing it from leaving said arm, a centrally disposed opening in said retaining means for allowing protrusion therethrough of at least a part of the lower portion of said lever arm, a horizontally disposed opening in said retaining means, disposed in juxtaposition with said actuating weight when said retaining means is moved vertically to discharge said weight therethrough, actuating means attached to said lever arm, working in conjunction therewith and disposed in a manner such that a movement of the lever arm is transmitted through said actuating means to actuate an extraneous device, thrust means on said arm for automatically returning the upper projecting portion of said lever arm back in contact with the channel back wall after the actuating weight has been discharged from said arm, and moving means attached to said retaining means for vertically moving said retaining means.

2. A weight actuated unit according to claim 1 in which the movable retaining means is a gate attached to the front side edges of said channel, holding means on said channel for holding said gate, and sliding means on said channel and gate to allow sliding of said gate in a vertical direction to discharge said weight while said gate is held by said holding means.

3. A weight actuated unit according to claim 1 in which the movable retaining means is a gate attached to the front side edges of said channel, flexible holding means on said channel for holding said gate and allowing said gate to be spread away from said channel, and rigid separating means on said channel sides for separating said

gate from said channel when the latter is moved vertically, separating the gate from the channel sufficiently to allow the weight held by the lever arm to drop down therebetween.

5. A weight actuated unit according to claim 1 in which the thrust means comprises an additional weight in the upper portion of said lever arm above the pivot, thereby causing an unbalance which causes said upper portion to contact the channel back when it is in idle position, said additional weight being only in such amount as to allow actuation of said lever arm by said actuating weight when the latter is dropped on said lever arm.

5. A weight actuated unit according to claim 4 in which the movable retaining means is a gate attached to the front side edges of said channel, a series of superimposed lever arms vertically disposed in said channel in over lapping relation to each other so that the lower end of the upper arm extends down to about the middle portion of the next lower arm, and the gate comprises a plate carrying said openings, said gate being disposed in front of said channel and slidably disposed upon the side edges thereof, side members projecting forwardly from the side edges of said plate, and oppositely disposed, inwardly-directed lips extending from the front edges of said side members and completing an enclosure through which said discharged weights may be passed, said lips being sufficiently close together to prevent egress of coins through the space therebetween.

6. A weight actuated unit according to claim 5 in which the front edges of the sides of the channel have oppositely disposed cut-out sections in the form of inclined plane surfaces by means of which the gate is separated horizontally from the channel as it is pulled thereover, and lips projecting from the front edges of the side members of the gate, disposed over and in juxtaposition with the inclined plane surfaces and serving as bearing surfaces for said gate.

7. A weight actuated unit according to claim 6 in which the forward portions of the sides of the channel have spring mountings, springs disposed on said mountings, an inclined plane surface disposed on each of the inwardly-directed lips extending from the front edges of the side members of said gate, and a projecting end on each spring disposed on the corresponding latter inclined plane surface of the gate in flexible retaining relation thereto.

8. A weight actuated unit according to claim 7 in which the moving means for said gate comprises an arm, a pivot mounted on said gate and to which one end of said latter arm is pivotally attached, a mounting on which the channel is mounted, a fixed pivot on said mounting to which the said latter arm is attached near its center and for which it acts as a fulcrum, and pulling means for pulling the other end of the latter arm in a vertical direction.

9. A weight actuated unit according to claim 1 in which the actuating means attached to the lever arm is a second lever arm extending from the pivot into space outside of said channel, for contacting an extraneous device located in said space.

10. A weight actuated unit according to claim 9 in which the first lever arm has, attached to it, forwardly projecting lugs extending from the sides of said arm at below the center of gravity of said lever arm, laterally directed holes in said lugs for housing the pivots, a wire disposed

through said holes and acting as the pivots for said lever arm, a flat loop in said wire behind the lower portion of said lever arm, and an extension of said wire from one of said pivots, extending in the form of a second lever arm into space outside 5 of said channel for contacting an extraneous device located in said space.

11. A weight actuated unit according to claim 1 in which the lower portion of the uprightly disposed lever arm is a flat, narrow, centrally-disposed strip of width narrower than that of the upper portion.
